UNITED STATES PATENT OFFICE.

ELIJAH MOUNTFORD AND CHARLES A. MAY, OF TRENTON, NEW JERSEY,
ASSIGNORS TO SAID MOUNTFORD AND JOSEPH BURROUGHS, OF SAME
PLACE.

DESIGN FOR ORNAMENTATION OF TABLE-WARE.

SPECIFICATION forming part of Design No. 14,962, dated April 15, 1884.

Application filed October 29, 1883. Term of patent 7 years.

To all whom it may concern:

Be it known that we, ELIJAH MOUNTFORD and CHARLES A. MAY, citizens of the United States, residing in the city of Trenton, in the county of Mercer and State of New Jersey, have invented a new and original Design for the Ornamentation of Articles of Table-Ware, and which is described in the following specification, and shown by the accompanying photographic illustrations.

The illustrations show ten different articles of table ware to the ornamentation of which our design is applied; but we do not limit ourselves to the ornamentation of the articles thus shown, as our design can be applied, and we do apply it, to any and all articles composing a table-service, and also to articles of toilet-ware.

Our design consists of an ivy-vine arranged in curves and with curving branches, to which vine and branches are attached ivy-leaves and curling tendrils, as shown in the illustrations. This ornamentation we place as a band about the body of the article to be ornamented, and,

where such article is provided with a cover, 25 in similar band about the cover. If the article is a plate or flat dish, we then place it in a band about the outer rim of such plate or dish, with a central ornamentation composed of ivy leaves and vines. 30

Figures 2, 4, and 10 show articles thus ornamented by such band about the body. Figs. 3, 5, 8, and 9 show articles thus ornamented, with covers thereon thus ornamented; and Figs. 1, 6, and 7 show articles thus ornamented 35 about the outer rim or edge, while at A, Fig. 1, B, Fig. 6, and at C, Fig. 7, is shown such central ornamentation.

What we claim as our invention, and desire to secure by Letters Patent, is— 40

In a design for table-ware and like articles, the ornamentation herein shown and described.

ELIJAH MOUNTFORD.
CHAS. A. MAY.
